REINFORCED-CONCRETE POLE-BASE.

1,268,325.

Specification of Letters Patent.

Patented June 4, 1918.

Application filed August 25, 1916. Serial No. 116,848.

To all whom it may concern:

Be it known that I, PHILIP H. COLE, a subject of the King of Great Britain and Ireland, residing at Shanghai, China, have 5 invented a certain new and useful Improvement in Reinforced-Concrete Pole-Bases, of which the following is a full, clear, concise, and exact description, reference being had to the accompanying drawings, forming a 10 part of this specification.

My invention relates to reinforced concrete pole-bases.

The invention is widely applicable for use in constructing telephone lines or transmission lines and in general where poles are employed to carry wires and the like. The invention is further applicable to use in bridge and trestle construction.

The wooden pole is poorly adapted for 20 direct setting in the ground due to the action of the air and moisture at the ground level which cause rotting of the pole at this point. The pole is also subject at or about the ground level to destruction by insects 25 and the like, particularly in tropical or semi-tropical regions.

The iron pole is subject to rusting at and below the ground level and in addition is expensive and unsatisfactory to install and 30 maintain, due to the requirement of special tools, etc. The iron pole is hard to climb and is dangerous to linemen due to its conductivity.

Concrete has recently been proposed as 35 material for poles. It is unsatisfactory in many respects like the iron pole, as it is expensive, and in that special steps must be provided for climbing the pole and special equipment must be provided for manufacturing, handling, installing and maintaining. Such poles are too heavy to transport and erect with unskilled labor and simple equipment. Concrete is a material which is 40 specially adapted for use at and below the ground level but which is poorly adapted for the shaft of the pole.

However, the iron and the concrete pole have their own special advantages and each type of pole has found a limited field of use.

50 I propose to construct a pole having the advantages of all three types of poles with a minimum of the disadvantages of each. The pole of my invention comprises a wooden shaft, a concrete base and an iron socket for 55 union between the base and the shaft. In

this manner I secure the benefits of the lightness and strength of the wooden pole in the shaft, the ease of climbing, of working or shaping and the valuable insulating properties. At the same time I secure the advantages of concrete construction at and below 60 the ground level. This also disposes the weight at the proper point and provides a rigid non-corrosive, non-rotting material at the surface of the ground. The iron socket 65 performs two functions. It forms first of all a socket for the wooden shaft, and at the same time it forms the reinforcement of the concrete base.

I shall now describe in detail one embodiment of my invention which is illustrated in the accompanying drawings which form a part of the present specification.

Figure 1 is a side elevation of a pole constructed in accordance with my invention;

Fig. 2 is a longitudinal section of the same;

Fig. 3 is a top plan view of the socket and base; and

Fig. 4 is a cross-section taken on the line 80 4, 4, of Fig. 2.

The pole of my invention comprises a concrete base 1 which is formed in a suitable mold as will be described later, a socket portion 2 and a wooden shaft 3.

The base 1 is hollow for the greater portion of its length having a tapering central bore 4, as shown in Fig. 2. The core which is employed to form this bore is tapered and diagonally split to facilitate withdrawal, being larger at the top than at the bottom.

A transverse passage 5 for the escape of water is formed in the sidewall near the bottom and communicates with the central bore 4.

The concrete base 1 is reinforced longitudinally by four angle iron bars 6, 7, 8, and 9 which are placed in the corners of the base 1 with the corners of the angle bars facing outwardly. These angle irons extend substantially the full length of the base and project out above the concrete to form the socket 2.

The base 1 is adapted to be set into the ground for a depth of about five feet according to the nature of the ground and the top of the base is then caused to project above the ground for a considerable distance so as to hold the pole well above the ground level. The corners of the base above the 110

ground level are chambered off as shown at 10, in Fig. 1, to indicate the proper setting depth.

The angle irons 6, 7, 8 and 9 are held together by an upper circumferential brace or strap of iron 11 which is riveted to the flat sides of the angles. A similar circumferential brace 12 is secured to the angle bars just at the point where they emerge from the concrete of the base 1. Two diagonal crossed braces 14 are riveted to each other and the adjacent legs of the angles upon each side of the base.

The angle bars 6, 7, 8 and 9 are reinforced at the point where they enter the concrete by short bars of angle-iron laid inside of and nesting with the angles 6, 7, 8 and 9. These short bars are continued for a short distance above and below the end of the base. The purpose of these short angles is to add strength to the iron and to add additional metal at the point most liable to rusting, the concrete being brought halfway up the band 12 in order to give extra strength at the point where the iron is liable to rust.

The angle bars 6, 7, 8 and 9 are tied together by a lateral reinforcing system of iron or steel wire 15 which in the form I have illustrated comprises a heavy wire wound helically about the angle bars 6, 7, 8 and 9.

The bottoms of the angle bars 6, 7, 8 and 9 are provided with short struts 16 which are attached diagonally. The function of these struts is to space the angles 6, 7, 8 and 9 properly while the concrete is being poured in the form about the core and skeleton and to act as a reinforcing brace.

The upper end of the central bore is flared out as shown at 17 in Fig. 2 to facilitate the draining of rain water running down the pole.

The pole base comprising the base 1 and socket 2 may be made in quantity at a central point and shipped to the point of use as the weight is not so great as to be prohibitive. The length is relatively small and the danger of breakage is slight.

The wooden shaft of the pole is trimmed to fit into the socket and is inserted either before or after the base is set into the ground. Suitable wedges not shown may be driven into the corners of the socket if desired and the pole may be fastened by spikes or screws although this is not generally necessary.

A pole base constructed in accordance with the above teaching is properly reinforced and as a consequence is both light and strong, being found of ample strength to withstand the severe uses to which poles in wire lines are commonly subjected. The construction is particularly permanent and saves its cost over other types of poles in a remarkably short time.

If the wooden shaft should become damaged as by lightning or other causes, another shaft may be substituted without disturbing the base.

I am aware that numerous attempts have been made to produce a pole base for securing the advantages of this type of construction but these devices have been of faulty design and are commercially unpractical. They are not adapted for convenience in construction or erection or handling by unskilled labor. I am the first to form a reinforcing system which projects out of the concrete well above the ground level and forms a socket for receiving the bottom of the wooden shaft.

It is apparent that I may form the base 1 suitable for round or square shafts. The number and size of the angle bars may be varied without departing from the invention.

While I have described the above embodiment of my invention with considerable particularity, I do not mean to confine myself to the dimensions or proportions shown nor do I intend to limit the invention any more than is required by the prior art, as I consider that numerous modifications and variations are possible without departing from the spirit and scope of my invention.

I claim:

1. In combination, a concrete base having its major portion adapted to be disposed below the surface of the ground, a plurality of angle bars symmetrically disposed in said base and forming reinforcing means for the base, the bars being disposed with their concave sides facing inwardly and projecting from the concrete to form a socket for receiving the shaft of a wooden pole, and circumferentially extending bracing means securing together and bracing the top of said angle bars with respect to each other, said bracing means lying wholly outside of the socket.

2. In combination, a hollow concrete base having its major portion adapted to be disposed below the surface of the ground, a plurality of angle bars symmetrically disposed in said hollow base and forming reinforcing means for said base, said bars projecting from said concrete to form a socket, reinforcing angles for reinforcing said first angle bars where they emerge from said concrete base, bracing means comprising circumferential and diagonal braces for securing the upper ends of said first angle bars together above the concrete and a round wooden pole having its lower end encircled and supported by said bars and braces.

3. In combination, a hollow concrete base having its major portion adapted to be disposed below the surface of the ground, said concrete base having a hollow bore, a plurality of angle bars symmetrically disposed

in said hollow base and forming reinforcing means for said base, said bars projecting from said concrete to form the corners of a square socket, means for supporting the lower ends of said angle bars, said concrete base containing wire reinforcement wound around said angle bars and bracing means for securing the upper ends of said angle bars together, said means comprising circumferential and diagonal braces exterior of concrete, said bars and braces forming a hollow socket adapted to surround and support the lower end of an individual wooden pole.

4. In combination a plurality of angle bars, a concrete base inclosing said angle bars for a portion of their length only, a circumferential band about said angle bars, at the point where they emerge from said concrete, said band being partially covered with the concrete to retard rusting, the top of the concrete being tapered away from said band to facilitate drainage of water from the band, and bracing means rigidly joining the upper free ends of the angle bars.

5. In combination a plurality of angle bars, a concrete base inclosing said angle bars for a portion of their length only, a circumferential band about said angle bars, at the point where they emerge from said concrete, said band being partially covered with the concrete to retard rusting, the top of the concrete being tapered away from said band to facilitate drainage of water from the band, and short reinforcing angle bars lying upon the opposite sides from said band and nesting with said plurality of angle bars at the point where the angle bars emerge from the concrete base, said reinforcing angles thereby protecting the adjacent side of the main angles against rust.

6. In combination, a plurality of angle iron bars arranged at the corners of a polygon, said angle bars having convex sides facing outwardly, circumferential reinforcing members about the lower ends of said

rod, a concrete filling surrounding and inclosing said reinforcing members and the lower ends of said bars only, a circumferential reinforcing member about the top of the bars, joining the free ends thereof and diagonal bracing bars joining the tops of the bars with the adjacent bars at substantially the point where they emerge from the concrete, the bars above the concrete together with their reinforcing members and bracing bars forming a socket adapted to receive and support without any bolts the lower end of a wooden telephone pole or the like.

7. In combination, a plurality of angle iron bars arranged at the corners of a polygon, said angle bars having their convex sides facing outwardly, circumferential reinforcing members about the lower ends of said rod, a concrete filling surrounding and inclosing the lower ends of said bars and said reinforcing members only, a circumferential reinforcing member about the top of the bars joining the free ends thereof and diagonal bracing bars joining the top of the bars with adjacent bars at substantially the point where they emerge from the concrete, the bars above the concrete together with the reinforcing members and bracing bars forming a socket, and an individual wooden pole stuck into and completely encircled by said socket, said pole being structurally unattached to said socket.

8. In combination, a concrete base having an axial bore opening at the upper end thereof, a plurality of symmetrically arranged angle bars embedded in said base about the bore and extending therefrom to form a rectangular socket and means for strengthening said angle bars adjacent the juncture of the same with said base and means interconnecting said bars at their free ends.

In witness whereof, I hereunto subscribe my name this 19th day of August, A. D. 1916.

PHILIP H. COLE.

Copies of this patent may be obtained for five cents each, by addressing the "Commissioner of Patents, Washington, D. C."

It is hereby certified that in Letters Patent No. 1,268,325, granted June 4, 1918, upon the application of Philip H. Cole, of Shanghai, China, for an improvement in "Reinforced-Concrete Pole-Bases," an error appears in the printed specification requiring correction as follows: Page 3, line 88, claim 8, after the word "ends" insert the words *said socket being adapted to hold a pole in alinement with the base*; and that the said Letters Patent should be read with this correction therein that the same may conform to the record of the case in the Patent Office.

Signed and sealed this 2d day of July, A. D., 1918.

[SEAL.]

F. W. H. CLAY,

Acting Commissioner of Patents.
